UNITED STATES PATENT OFFICE.

MICHAEL HALLANAN, OF NEW YORK, N. Y.

HORSESHOE-SHAPING DEVICE.

SPECIFICATION forming part of Letters Patent No. 681,545, dated August 27, 1901.

Application filed January 28, 1901. Serial No. 45,050. (No model.)

To all whom it may concern:

Be it known that I, MICHAEL HALLANAN, a citizen of the United States, and a resident of the city of New York, borough of Manhattan, 5 in the county and State of New York, have invented new and useful Improvements in Horseshoe-Shaping Devices, of which the following is a full, clear, and exact description.

The object of the invention is to provide a 10 tool wherewith horseshoers may expand or contract a horseshoe at the quarters to fit the peculiarities of the hoof. It is well known that the greatest difficulty in fitting a horseshoe is due to the infinite variety in the lines 15 of horses' hoofs at the quarters.

Although my invention is useful with horseshoes in general, it has special advantages in connection with the improved shoe illustrated in an application filed by me concurrently 20 herewith; and the novel features will be hereinafter fully described in connection with said improved shoe and then defined in the claims.

Reference is to be had to the accompanying drawings, forming a part of this specification, 25 in which similar characters of reference indicate corresponding parts in all the figures.

Figure 1 is a plan view of a tool embodying my invention, showing the same applied to a shoe on the under side of the latter for the 30 purpose of expanding said shoe at the quarters. Fig. 2 is a cross-section taken through the tool and shoe on the line 2 2 of Fig. 1. Fig. 3 is a cross-section taken through the shoe on the same line as Fig. 2 is taken and 35 showing in cross-section a contracting-tool operated by the same devices as the expanding-tool. Fig. 4 is a side elevation of the tool, on a larger scale, without either the expanding-heads or contracting-clamps; and Fig. 5 is 40 a plan view of one of the contracting-clamps.

Briefly described, the shoe illustrated comprises a backing 10, of leather, a facing 11, of rubber, an intermediate layer 12, of canvas, and a metallic segment 13, forming the front 45 section of the tread, the quarters 14 being of rubber. The metallic segment is formed with a rearwardly-extending arm 15, which is riveted to the rubber, &c., as by rivets 16. In order that the shoe may have increased 50 yieldingness at the quarters to permit contraction and expansion, the leather backing

10 is cut away, as at 17, at points inside the rubber quarters 14.

To expand or contract the quarters, I provide the tool shown, consisting of a lever-handle A, having cheeks a at its forward end, through which passes the spindle B, having right and left threads at its ends. Between the cheeks a there is secured on the spindle B three ratchet-wheels C C', of which the 60 teeth on the end wheels face oppositely to the teeth of the intermediate wheel C'. A spring-pawl D on one side of the lever-handle engages the ratchet-wheels C, and a pawl D' on the opposite side of the handle engages the 65 ratchet-wheel C'. The teeth of the intermediate wheel C' are disposed out of line with the teeth on the outer wheels C. The spring-pawls D D' are secured by thumb-screws D² and formed with slots d, so that either pawl 70 may be thrown into action.

With the described ratchet mechanism I employ either the expanding-heads E E or the contracting heads or clamps F F. The heads E fit inside the quarters 14 and have threaded 75 sockets e, engaging the right and left threads on the spindle B, so that when the spindle is rotated in one direction by the ratchet mechanism described the heads E will be forced outward and expand the shoe at the quarters. 80 The heads or clamp-blocks F have similar threaded sockets f, formed in elongated arms F', and by turning the spindle B in the proper direction the clamps will be drawn together and contract the quarters. It is to be understood that the shoe is nailed when the quarter has been brought to the proper lines. In 85 this manner one side of the shoe may be expanded and secured and the opposite side contracted and secured. 90

The bearing-surfaces e' of the expanding-heads are on the outside and the bearing-surfaces f' of the clamps are on the inside, and said bearing-surfaces are curved laterally to properly effect an engagement with the 95 shoe whereby the desired change in the lines in the hoof may be brought about.

Having thus described my invention, I claim as new and desire to secure by Letters Patent

1. A tool for fitting horseshoes at the quarters, comprising separate spaced heads hav-

ing bearing-surfaces respectively fitting the opposite quarters of a horseshoe, and means extending between the said heads for moving the heads toward and from each other, the heads having the bearing-surfaces curved laterally.

2. A horseshoe-shaping device comprising heads for engaging the quarters of a shoe, a spindle engaging the heads by right and left threads, and means for turning the spindle, the heads extending forward and rearward

from the point of engagement with the spindle, and having each a bearing-surface curved longitudinally, substantially as described.

In testimony whereof I have signed my ¹⁵ name to this specification in the presence of two subscribing witnesses.

MICHAEL HALLANAN.
